UNITED STATES PATENT OFFICE.

JOHN T. SIMPSON AND MARSHALL N. SHOEMAKER, OF NEWARK, NEW JERSEY.

FIREPROOF BUILDING.

SPECIFICATION forming part of Letters Patent No. 737,670, dated September 1, 1903.

Application filed April 23, 1903. Serial No. 153,913. (No model.)

To all whom it may concern:

Be it known that we, JOHN T. SIMPSON and MARSHALL N. SHOEMAKER, citizens of the United States, residing at Newark, in the county of Essex and State of New Jersey, have invented certain new and useful Improvements in Fireproof Buildings, of which the following is a specification, such as will enable those skilled in the art to which it applies to make and use the same.

Our invention relates to the construction of fireproof walls, partitions, and the like composed of concrete and reinforcing elements of metal, the essential points thereof being to provide a wall construction in which shall be employed the minimum amount of both concrete and metal to produce the desired strength and fireproof qualities and in which the usual foundations required to support ordinary masonry walls can be omitted and an economical, strong, fireproof, and self-supporting construction substituted in which all the metal parts used are thoroughly embedded in and protected by the concrete or similar plastic materials.

A further object of our invention is to provide a simple and economical means of forming walls in imitation of stonework and in which the usual centering can be disposed of entirely by forming the walls of blocks made in the desired shapes in molds and setting the blocks in place after they have become hardened.

The invention is fully disclosed in the following specification, of which the accompanying drawings form a part, in which the separate parts of our improvement are designated by suitable reference characters in each of the views, and in which—

Figure 1 is an elevation of a portion of a wall construction, showing the finished exterior surface, with reinforcing metal members shown by dotted lines. Fig. 2 is a vertical section of the construction, taken on line 2 2 of Fig. 1. Fig. 3 is a horizontal section of the wall construction, taken on the line 3 3 of Fig. 1. Fig. 4 is a plan view of the top edge of the blocks forming the wall construction and showing the groove for an anchor to attach the blocks to the tension-bars. Fig. 5 is an enlarged elevation of the blocks, showing the

reinforcing metal and means of connecting the blocks to the metal tension-bars. Figs. 6 and 7 are vertical sections of the blocks shown in Fig. 5 and show the method of attaching the reinforcing-rods to the metal tension-bars. Fig. 8 is an enlarged section of the metal column, taken on line 8 8 of Fig. 1, and shows the method of attaching the metal tension-bars to the column, also the manner of embedding and protecting the metal column. Fig. 9 is an enlarged vertical section of Fig. 1, taken on line 9 9 and showing the method of forming lintels and window-heads. Fig. 10 is an enlarged horizontal section of Fig. 1, taken on line 10 10 and showing the method of attaching the metal tension-bars to the metal framing at window-openings. Fig. 11 and Fig. 13 are enlarged partial vertical sections of Fig. 5 and show another method of attaching the blocks to the metal tension-bars. Fig. 12 is an enlarged vertical section of Fig. 1, taken on line 12 12 and showing the method of attaching the blocks to the metal frame of the window-sill.

Referring to the drawings, A represents the supporting-piers, upon which the metal columns B of the building construction rest in the usual manner and upon which are placed the reinforced concrete girders C, spanning from pier to pier and forming a water-table base and support for the blocks D of the wall construction. These girders C are composed of concrete reinforced with metal bars 2, which bars pass from end to end and are embedded in the lower side of the concrete forming the bulk of the girders, together with metal binders 3, spaced at certain distances apart in the length of girders C and having one end bent into the form of a hook a, which passes over the metal tension-bars 4 of the wall construction and is attached thereto.

Between the upright columns B are placed the metal tension-bars 4, which in the preferred form are round bars, but may be square, flat, I, L, or T shaped rods or a pair of wires twisted together. These rods 4 are attached to the columns B in some suitable manner and are spaced at certain distances apart and run parallel with the girders C.

Upon the supporting-girders C and between the metal tension-bars 4 are placed the con-

crete or similar blocks D, having grooves C² so arranged in their top and bottom edges that when they are set out in place the main tension-bars 4 will act in tension and the concrete blocks D in compression when the sides of the building are subjected to a wind-pressure from without, and these blocks D are set in cement-mortar joints e in the usual manner. The blocks D may be made solid, as shown in Figs. 2, 3, 4, 6, 8, 9, 10, 11, 12, and 13, or cellular, as shown in Fig. 7, the latter being designed to do away with the usual furring of walls. The outside surface of the blocks D may be finished in any imitations of stonework and colored as desired. In the blocks D are embedded diagonally placed reinforcing-rods 5, having their upper ends bent into the form of a hook, as shown at a, Fig. 2, 6, 7, and 12, which hooks a pass over the bars 4 and secure the blocks D in place. When these blocks D are made very thin, an additional binding material 6, consisting of a metal fabric, is placed directly against the diagonal reinforcing-rods 5. Where the blocks can be made thick, a separate anchor of metal 7 may be used in place of the hook a of the reinforcing-rod 5, as shown in Figs. 11 and 13. A hole b is provided in the blocks D to receive these anchors, which are set in a cement joint e. The blocks D are formed in a wood or metal mold, and the concrete forming the outside or finished surface of the blocks being placed in the forms first make it possible to use a very thin coat, and upon this facing coat is then placed the concrete forming the bulk of the blocks and in which are embedded the reinforcing-rods 5 and metal fabric 6 as the blocks are formed. A finished surface can be put on the inner side of the blocks, if desired, in the same way.

The blocks E, forming the pilasters and column protection on the face of the wall, are formed similar to blocks D and attached to the bars 4 in the same manner.

The interior protection of the columns B may be made of blocks similar to blocks D or formed, as shown, by casting solid concrete Fabout same, thoroughly embedding all metal parts in this material. The door or window sill G can be formed similar to blocks D and anchored to the tension-bars 4 by means of hook-bolts 8, as shown in Fig. 12. The openings for doors and windows have a metal frame H, made of angles or other suitable shapes and having holes to receive the main tension-bars 4, Fig. 10, or anchor-bolts 8, Fig. 12. The blocks D, sills G, and lintels J have edges formed to fit against these frames H. Provision is made to secure the nailing-stripes

K and to provide means of attaching the window or door frames M.

When it is desirable to use the wall construction for more than one story in height, the supporting-girders C can be repeated at each floor-level, or the usual steel-girders used in skeleton constructions may be used in their place to support the weight of the construction.

Having fully described our invention, what we claim as new, and desire to secure by Letters Patent, is—

1. In a building construction, piers arranged at intervals, girders formed of concrete reinforced with steel and resting on said piers, concrete blocks reinforced with steel and resting on said girders, and horizontal metal tension-bars placed horizontally and in the joints between the said blocks, said girders and blocks being also provided with vertically - arranged binders, substantially as shown and described.

2. The combination in a wall or partition construction, of concrete or similar plastic materials formed into blocks and reinforced with metal, girders formed of concrete reinforced with metal rods in the lower side thereof to take the tension stress and wherein the concrete takes the compressive stress, binders which pass under the metal tension-rods and up to the upper edge of the girders where one end is bent into the form of a hook which passes over a main tension-bar of the wall construction and anchors the bar firmly to the girders, main tension-bars passing between and attached to upright columns which bars are spaced at certain distances apart and parallel to the supporting-girder, blocks formed of concrete and having a groove in the top and bottom edges to receive the main tension-bars and a groove in the end edges to receive a key of cement in which the blocks are set, metal reinforcing-rods bent at the top end into the form of a hook which passes over and secures the blocks to the main tension-bars, and a reinforcing metal fabric embedded in said blocks to afford additional strength, substantially as shown and described.

In testimony that we claim the foregoing as our invention we have signed our names, in the presence of the subscribing witnesses, this 16th day of April, 1903.

JNO. T. SIMPSON.
MARSHALL N. SHOEMAKER.
